NICOLAI PETERSEN, OF COLUMBUS, MISSISSIPPI.

Letters Patent No. 64,360, dated April 30, 1867.

MUSICAL DIAL.

The Schedule referred to in these Letters Patent and making part of the same.

TO ALL WHOM IT MAY CONCERN:

Be it known that I, NICOLAI PETERSEN, of Columbus, in the county of Lowndes, and State of Mississippi, have invented a new and improved Musical Dial; and I do hereby declare that the following is a full, clear, and exact description thereof, which will enable others skilled in the art to make and use the same, reference being had to the accompanying drawings, forming part of this specification, in which—

Figure 1 represents a front elevation of this invention.

Figure 2 is a transverse section of the same, the line x x , fig. 1, indicating the plane of section.

Figure 3 is a detached elevation of the movable disk.

Similar letters of reference indicate like parts.

This invention relates to a dial which exhibits all musical sounds or tones, as regards their names and distances from one to the other, in a circle, the various kinds of scales being distinguished by the different colors. A movable dial combined with the stationary dial allows of setting the device for different key-notes.

The principal scales used in music are as follows: first, the chromatic scale, comprising all recognized tones, at intervals of half steps; second, the diatonic major scales, consisting of whole and half steps, viz, two whole, one half, three whole, and one half step; third, the diatonic minor harmonic scales, consisting of one whole, one half, two whole, one and one-half, and one half steps; fourth, the diatonic minor melodic scales, ascending, which consist of one whole, one half, four whole, and one half step; fifth, the diatonic minor melodic scales, descending, though counting from one upwards, consisting of one whole, one half, two whole, one half, and two whole steps. The chromatic scale is indicated by a blue belt, which is divided in twelve parts, each representing one half step. On the outside of said belt are marked the names of the various tones, with sharps ($\sharp$) and flats ($\flat$) between them, and suitable arrows, pointing from the adjoining letters towards said sharps ($\sharp$) and flats ($\flat$) indicate the names C sharp, D flat, D sharp, E flat, and so forth. The second or green belt on the main dial A represents the diatonic major scale; the third belt, the diatonic minor harmonic scales; the fourth belt, the ascending, and the fifth the descending minor melodic scales. The minor dial B is arranged so that it revolves on its axis, and it is marked with figures, from one to seven; which, as said dial is turned, are visible through holes in the stationary dial A. By means of the dial B it can readily be shown that all the scales of their kind, major and minor, are the same in measurement, and said dial helps to remove the idea that all scales differ on account of their larger or smaller number of flats or sharps.

By turning the dial, it will give all major, with their relative minor scales ascending and descending, and the transposition of scales is thereby materially facilitated. Having the figure 1 on the movable dial B brought in such a position that it stands opposite to C on the major scale, the outer figures will give the scale of C major, and the inner figures will give its relative minor scales in A in all its forms. By turning figure 1 opposite to G, the G scale will be formed with one sharp, and by continuing to turn or transpose from 1 to 5, new scales are formed and a new sharp is added at every turn, until seven sharps are gained in the key of C $\sharp$. Going back to C, and then turning 1 to 4, or F, one flat will be found in the scale, and by continuing 1 to 4, all the scales with flats will be found. The relative minor scales will always follow. One rule must be observed, viz, that all letters must occur in all the scales, whether natural, flat, or sharp, and consequently none twice. For this reason, some letters must sometimes be called double sharp, ($\natural\sharp$) such as the C, F, and G double sharps, which occur in the D $\sharp$, G $\sharp$, and A $\sharp$, minor scales.

What I claim as new, and desire to secure by Letters Patent, is—

1. A musical dial, substantially as and for the purpose described.
2. The combination of the movable dial B with the stationary main dial A, as and for the purpose set forth.

The above specification of my invention signed by me this 22d day of October, 1866.
